UNITED STATES PATENT OFFICE.

THOMAS HARRISON SYMINGTON, OF BALTIMORE, MARYLAND.

DRAFT-GEAR.

1,097,738.

Specification of Letters Patent. Patented May 26, 1914.

Application filed March 4, 1912. Serial No. 681,528.

To all whom it may concern:

Be it known that I, THOMAS H. SYMINGTON, a citizen of the United States of America, residing at the city of Baltimore, State 5 of Maryland, have invented certain new and useful Improvements in Draft-Gears, of which the following is a specification.

The object of the invention is to provide a draft rigging for cars which is simple in 10 construction and of increased efficiency and length of life.

In the draft gear of my invention there is a horizontal yoke fastened to the draw-bar, a key passing through elongated slots 15 in the sills and corresponding slots in the yoke, the key serving as a front stop for the shock-absorbing means.

In the preferred form of my invention the draw-bar is fastened to the yoke by means 20 of a front key, and abutments on the sills serve to limit the motion of the front key. A rear key, seated in elongated slots in the sills and corresponding slots in the yoke, serves as a front stop for the spring or friction gear. At the rear the spring bears 25 against the yoke or a follower thereon, and as a rear stop there is a fixed abutment on the frame of the car which serves to arrest the rearward movement of the rear follower 30 or yoke.

Another feature of my invention relates 35 to an improved friction barrel and yoke guide inclosing the shock absorbing member. This is in the form of two or more straps or bands extending from one sill or draft beam to the other above and below the yoke. These bands have horizontal portions which serve as a yoke guide, and between the arms of the yoke the upper bands 40 are bowed upward while the lower bands are bowed downward, forming a spring or friction casing composed of the concave surfaces of the bands and the inner surfaces of the arms of the yoke.

45 In the accompanying drawings I have illustrated a draft gear embodying my invention in its preferred form. In connection with the draft gear I have shown so much of the frame of a car as is necessary to 50 the illustration of the operation of my invention.

Figure 1 is a view half in plan and half in horizontal cross-section on the line 1, 1 of Figs. 2 and 3. Fig. 2 is a vertical section 55 on the line 2, 2 of Fig. 1. Fig. 3 is a trans-

verse vertical section, one half being taken on the line 3, 3 looking in the direction of the arrows, the other half being taken on the line 3', 3', also looking in the direction of the arrows thereon. Fig. 4 is a fragmentary 60 longitudinal section showing a slightly different construction.

In connection with the draft gear I have shown draft beams or sills 1 and front sills 2. The sills are provided with a pair of 65 alined, elongated slots 3 to receive a front key 4, and a second pair of alined elongated slots 5 in which is seated a rear key 6, the front and rear ends of the slots are herein referred to as abutments. A yoke 7 is in 70 the space between the sills. The arms of the yoke are provided with two pairs of alined, elongated slots 8, 8 and 9, 9 corresponding to the slots 3, 3 and 5, 5 in the draft beams. It will be noted that the forward slots 3 75 in the draft beams exceed in length the rear slots 5. The slots in the yoke are of a length slightly in excess of that of the rear slots 5 in the draft beams. The draw-bar 10 is provided with a slot 11 of a size to fit 80 the front key 4, and the latter passes through the front slots 8 of the yoke and through the draw-bar, being seated in the front slots of the sills as described. The rear key 6, which is described as seated in the rear slots 5 of 85 the draft timbers, passes through the rear slots 9 of the yoke and carries the front follower 12 which is slotted at 13 to receive and fit the key. The rear end of the draw-bar bears against the front of the follower, and, as shown, the latter is provided with 90 a tongue or extension 14 fitting a corresponding socket 15 in the end of the draw-bar.

Secured to the sills or draft timbers, extending from one to the other in the rear of the yoke, is a rigid member 16 which forms the rear stop for the draft gear. This member is provided with a stop surface 17 95 against which the rear face 18 of the yoke bears when the gear is in normal position and strikes during the act of buffing. The rear follower 19, as shown, is in the form of a flat rectangular block slotted at its edges at 20 to receive the yoke. This follower 100 bears against the rear arm 7' of the yoke which, as described, in normal position and in buffing, preferably bears against the rear abutment 16. Within the yoke between the 105 opposed surfaces 21 and 22 of the front and 110

rear followers, respectively, is a shock absorbing member 23. This may be in the form of a spring or any suitable friction gear, and is indicated in a conventional manner. This gear is supported and held in position by means of bands or plates which in close the yoke above and below, forming a friction or spring pocket, and at the same time serving as a guide for the arms of the yoke. These straps or bands 24 and 25 extend transversely and are secured at their ends to the sills. Adjacent the sills there is a horizontal portion or bearing 26 on each band. These horizontal surfaces or bearings engage the top and bottom faces of the yoke arms and serve as a yoke guide. Between the bearing surfaces 26, the plates are deflected, the upper ones upward and the lower ones downward, preferably in a circular arc, so that their inner surfaces, combined with the inner faces of the yoke arms, form a substantially cylindrical casing within which the spring or friction gear is inclosed.

Fig. 4 illustrates an alternative form of follower which also serves as a yoke guide or support. This follower 28 is provided with rearwardly extending arms 29 and 30 having horizontal guiding surfaces 31 and 32. The follower arms 31 and 32 inclose the rear arm of the yoke and the rear abutment or stop member 16, and engage corresponding upper and lower horizontal guiding surfaces 33 and 34 on the member 16. The follower thus mounted serves as a guide and support for the yoke.

The operation of the gear will be clearly apparent from the description taken in connection with the accompanying drawings. The gear is shown in normal position, that is, the position which it would take when subjected to no stress. In drawing, the stress is transmitted from the draw-bar to the front key 4, hence to the yoke by which it is applied to the rear follower. The rear follower compresses the spring or friction gear and transmits the stress to the front follower which is mounted on the rear key 6, the latter serving as a forward abutment. It will be noted that in normal position this key rests against the front surfaces of the slots 5 in the draft beams. As drawing is continued and the gear is compressed, the front key moves forward toward the front ends of the slots 3 in the draft beams, and under extreme stress both keys bear against the front ends of these slots and the stress is applied direct to the sills at four points, and if any portion of the gear fails, the front key forms a rigid connection between the draw-bar and sills. This prevents pulling out of the draw-bar.

In buffing, stress is first applied by the draw-bar to the front follower 12 which transmits stress through the resilient gear to

the rear follower 19 and through the rear arm 7 of the yoke to the fixed abutment 16. Under extreme buffing stress, the rear key moves back and engages the rear ends of the slots 5, and the front key 4 moves to its extreme rear position and engages the rear ends of the slots 3, so that stress is applied to the sills direct from the draw-bar at the four bearing points of the keys and by way of the resilient gear through the rear arm of the yoke to the rear abutment 16. It will be noted that the slots in the yoke which receive the keys are so placed and are of such extent that compression is never applied to the arms of the yoke.

I have thus described in minute detail a single embodiment of my invention in order that its nature and operation may be clearly understood. However, the specific terms herein are used in their descriptive rather than in their limiting sense, and the scope of the invention is defined in the claims:

I claim—

1. In a draft gear, a draw-bar, draft beams, followers, a horizontal yoke connecting the rear follower to the draw-bar, a compressible member between the followers, and means for guiding the yoke and inclosing the compressible member consisting of a strap secured at its ends to the draft beams and deflected upwardly between the beams, and a similar strap deflected downwardly between the beams and secured at each end to the beams, the straps having shoulders, one at each side of the deflected portion, the shoulders forming upper and lower guides for the yoke.

2. In a draft gear, a draw-bar, draft beams, stops, a horizontal yoke, a compressible member within the yoke between the stops, and a support and guide for the compressible member and yoke consisting of a strap deflected downwardly between the beams to inclose the compressible member and secured at each end to the beams, and having at each side of the deflected portion a shoulder to engage the corresponding arm of the yoke and act as a guide and support for the same.

3. In a draft gear in combination, a horizontal yoke, a draw-bar, keyed to the yoke and having a limited sliding engagement relatively thereto, a front stop in the form of a key passing through the yoke and sills and having play in both, a rear stop extending from one sill to the other and secured to the sills, the rear arm of the yoke having a bearing against the rear stop during buffing, a follower within the yoke, a resilient member compressed between the front stop and the follower, the latter bearing against the rear arm of the yoke which transmits pressure from the follower to the rear stop, the follower having horizontal arms above and below the yoke which engage bearing sur-

faces on the top and bottom of the rear stop and serve as a guide and support for the yoke and follower.

4. In a two-key draft gear in combination, 5 sills and cheek plates secured thereto, a horizontal, integral, U-shaped yoke, a rigid abutment or rear stop against which the rear face of the yoke abuts normally, the abutment being connected to the inside faces of the sills, 10 the cheek plates being short and having two sets of aligned slots, one immediately in the rear of the other, the plate terminating immediately in the rear of the rear slot and well forward of the rear abutment, the yoke 15 having slots corresponding to those in the cheek plates, a slotted draw-bar, a key seated in the slot engaging the forward slots in the sills and yoke to transmit drawing stresses to

the yoke, the draw-bar being free to move rearwardly relatively to the yoke in buffing, 20 the second key seated in the rear slots in the sills and yoke so that the yoke is free to move relatively to it in drawing, the rear key serving as a front stop and having a front follower supported thereon, means for 25 supporting the rear end of the yoke independently of the keys, a rear follower engaging the rear arm of the yoke, and a resilient member between the followers.

Signed at Baltimore, Maryland this 27th 30 day of February 1912.

THOMAS HARRISON SYMINGTON.
